UNITED STATES PATENT OFFICE.

ELLIOTT B. CLARK, OF WELDON, NORTH CAROLINA.

MOTION-PICTURE REEL.

Application filed October 17, 1919, Serial No. 331,283. Renewed August 7, 1922. Serial No. 580,278.

To all whom it may concern:

Be it known that I, ELLIOTT B. CLARK, a citizen of the United States, residing at Weldon, in the county of Halifax and State of North Carolina, have invented certain new and useful Improvements in a Motion-Picture Reel, of which the following is a specification.

This invention has relation to certain new and useful improvements in film reels, the object of my invention being to provide an improved film-winding reel which is interchangeable with an ordinary film-feeding reel, and to connect the winding reel to the feeding reel through the medium of suitable gearing to cause these reels to rotate at the same speed, thereby eliminating the services of one man now necessary to rewind the film.

With these and other objects in view, the present invention consists in the combination and arrangement of parts as will be hereinafter more fully described and finally pointed out in the appended claims, it being further understood that changes in the specific structure shown and described may be made within the scope of the claims without departing from the spirit of the invention.

In the accompanying drawings forming a part of this specification and in which like numerals of reference indicate similar parts in the several views:

Figure 1 shows a side view with parts broken away, of a reel embodying my invention, positioned and arranged for use as a feed reel or paying-out reel.

Figure 2 is an edge view partly in vertical section.

Figure 3 is a detail of the film clamp, Figure 4 shows the clamp in position.

As shown in the drawings I employ a casing comprising a back plate 10, from which extends the tubular hub 11, this hub having the access slot α .

Revolutely surrounding this hub 11 is the reel proper comprising the outer plate 9, having the radially disposed slots ν , and fixed to this plate 9 is the belt pulley 8 receiving the belt 7, by means of which the pulley is rotated. The belt 7 is driven by any appropriate means (not shown) and connects this pulley 8 with another pulley 8 (not shown), of the same diameter, of an ordinary paying-out reel or one of the kind of reels here shown; these similar reels be-

ing used alternately and interchangeably as feed-reels and winding-reels.

Communicating with the hub 11, is the chute 13, this chute being laterally offset as shown, the intake end of the chute being opposite the slot α in the drum or hub 11.

Situated opposite the intake end of the chute 13 are the rolls 6, 6, while located adjacent to the slot α are the rolls 5, 5, these rolls guiding the film into the chute laterally as shown in Figure 2.

Held to the reel is the film holder 15 comprising a slotted member which is tightened by means of the wing nut 4 on the threaded end 3 of the holder 15.

Each of the slots ν is adapted to receive a similar one of the holders 15, but only one of such holders is here shown, the others being removed and not shown. These film-holders are radially adjustable in the slots ν , to compensate for films of different lengths (viz film-coils of different inner and outer diameters). The reel-holders are also shiftable from the outer periphery of the coil to its inner periphery, so that when the film has been fully wound onto the reel, around the holders 15, these holders can then be shifted to the exterior of the coil, and one of the holders caused to clamp the outer end of the coil, (as shown in Fig. 1), and then the two interchangeable reels are reversed as to their respective functions; that is, the empty one is used as the winding reel, and the full one is used as the feed-reel, the film being fed from the center of reel and interior of coil, through the chute 13, and the empty reel takes up the unwound part of the film and winds it in the outer sides of the holders 15. Each pic-

ture show could have a stock of these reels and wind from reel now in use on to this reel and thence to a similar reel and show as many times as wanted, then rewind on original reel at his leisure—after the show was over. This would do away with the use of one man, and consequently cut down expenses.

While the illustration and description of this invention is confined to a certain degree of particularity it is to be realized that in practice various alterations and changes may be made, and therefore the right and privilege of changing the form of the details of construction and otherwise altering the arrangement of the correlated parts is reserved without departing from

the spirit of the invention or the scope of the appended claims.

Having thus described my invention, what is claimed as new and upon which Letters Patent are solicited is:

1. In a reel for winding and paying out films, a hollow hub provided with radial openings, a film guiding roller at one of said hub openings, and a coil-forming device normally seated to rotate on said hub and to hold the film-coil in position to encompass one of said openings, the other of these openings being off-set from the rotary plane of the coil-forming device so that an uncoiled part of the film can pass through said hub from one to the other of said openings and thence out by the side of the coil, said coil-forming device being provided with adjustably mounted film holders that are shiftable from the interior to the exterior of the coil for holding the film either in position to be unwound from the interior

of the coil, or to be wound thereon in successive outer convolutions.

2. In a reel for alternately winding and paying out films, a hollow hub provided with substantially radially opposite film-outlets, one of these outlets being provided with film-guiding rollers, the other being provided with a radially disposed film-guiding chute, a film-coiling device normally journaled on said hub, and a plate fixed on and surrounding said hub and serving to guide the film as it is being coiled and paid out, said outlets being disposed at opposite sides of the said plate, and spaced guides carried by said hub and extending through said plate, the space between these guides being substantially alined with said outlets.

In testimony whereof, I affix my signature.

ELLIOTT B. CLARK.
